(57) **CLAIM**

The ornamental design for a hook for hanging ornamental objects, as shown and described.

DESCRIPTION

FIG. 1 is a left-front top perspective view of the hook for hanging ornamental objects;

FIG. 2 is a front view of the hook for hanging ornamental objects;

FIG. 3 is a back view of the hook for hanging ornamental objects;

FIG. 4 is a top view of the hook for hanging ornamental objects;

FIG. 5 is a bottom view of the hook for hanging ornamental objects;

FIG. 6 is a right side view of the hook for hanging ornamental objects;

FIG. 7 is a left side view of the hook for hanging ornamental objects;

FIG. 8 is a right-back top perspective view of the hook for hanging ornamental objects; and,

FIG. 9 is a left-front top perspective environmental view of the hook for hanging ornamental objects.

The broken lines depict the hook for hanging ornamental objects in an unclaimed environment of use.

1 Claim, 7 Drawing Sheets
